UNITED STATES PATENT OFFICE.

ALBERT B. HALSTED, OF HOBART, NEW YORK.

SEAT-FASTENER.

SPECIFICATION forming part of Letters Patent No. 320,243, dated June 16, 1885.

Application filed January 27, 1885. (No model.)

To all whom it may concern:

Be it known that I, ALBERT B. HALSTED, a citizen of the United States, residing at Hobart, in the county of Delaware and State of 5 New York, have invented a new and useful Improvement in Seat-Fasteners, of which the following is a specification.

My invention consists of a hook-stud and a key-latch on one side of the seat-risers, in combination with a box-cleat on the corresponding side of the rails whereon the risers rest, and being so contrived that in putting the seat in its position the hook-studs will drop through the recesses of the box-cleats and hook under 15 the cleats at one end, and the key-latches will also drop through said recesses and wedge by their gravity against the other end to bind the hook-studs fast and to be themselves kept in position by the same means, said key-latches 20 being connected to the risers by a pivot whereon they swing up and down to release or fasten the seat; and they are provided with a thumb-bit by which to lift them, and with a guard-cleat 25 for protection and support. Said cleats are also contrived to serve for stays to the hook-studs and for protection of the pivots of the key-latches against thrusts of the seat in the forward direction, all making a very simple and effective fastening device for removable or 30 detachable seats of wagons and other things or places in which such seats are used, as hereinafter fully described, reference being made to the accompanying drawings, in which—

Figure 1 is a transverse section of a wagon-seat and an inside elevation of part of one side of a wagon-box, showing one of the fasteners in side elevation as when the seat is fastened. Fig. 2 is a similar view as when the seat is being put in position to illustrate the operation 40 of the fastener. Fig. 3 is a horizontal section of the seat-riser, showing the fastener in top view, and Fig. 4 is a top view of the seat-rail and the box-cleat of the fastener.

On the inside of the seat-supporting rail *a*, 45 and flush with the upper edge, or nearly so, I arrange and secure a box-cleat of metal, *b*, having a recess, *c*, of suitable length and extending through it vertically, and on the seat-riser *d*, I arrange a hook-stud, *e*, and a fastening-key, 50 *f*, to engage with the box-cleat and secure the seat on the rail, the hook-stud being so fitted

that its head *g* will shift under the cleat back of one end of the recess *c*, after passing through the same to hold the seat down, and the key being so that it will drop into the recess and wedge fast against the other end of the recess when the head of the hook-stud shifts back, and secure it in that position. The hook-stud is permanently fastened to the side of the riser, 55 so as to project vertically downward therefrom; but the key is a curved prong of a latch-bar, *h*, that extends along the seat-riser in the opposite direction of the hook-stud *e* a suitable distance to a pivot, *i*, whereon it is mounted for a support, on which it may swing for shifting the key *f* in and out of the box-cleat; and the key-latch thus contrived is arranged within the guard-cleat *j*, firmly secured to the riser, 60 for the protection of said latch and for a stay to the hook-stud *e*. The guard-cleat *j* has a curved recess, *k*, extending from top to bottom, 65 for the key to work through. It also has a horizontal recess, *l*, along the upper edge to allow the bar *h* to drop in flush with the upper side, and it also has the notch *m* in the upper 70 edge to allow the thumb-bit *n*, attached to the key-latch for lifting it, to fall in. The edge of the key *f*, working against the curved shoulder *o* of the box-cleat *b*, is a little eccentric to said shoulder, so as to wedge against it and 75 crowd the hook-stud *e* home on shoulder *p*, to hold it firmly and prevent rattling, and the upper end of the key closes in snugly against shoulder *q* of guard-cleat *j*, so that the shoulder takes the effect of the forward thrusts of 80 the seat and relieves the latch-pivot of them. The opposite thrusts are resisted by the hook-stud *e* and shoulder *p* of the box-cleat.

The hook-stud is to be boxed into or otherwise suitably connected with the rear end of 85 the guard-cleat, to be firmly stayed thereby in its connection with the seat-riser *a*.

The key-latch *f* *h* is pivoted on the fastening-bolt *i*, and the hook-stud *e* may be secured by the fastening-bolt *t* of the guard-cleat; or it 90 may be made integral with said cleat.

It will be seen that all the parts are of very simple contrivance, adapted for being made in the cheapest manner by casting them in malleable iron or steel, and they require no fitting 95 except boring the holes for the bolts employed to fasten them on the respective parts to which 100

they belong. There are no detachable parts that are liable to be lost. All the parts are strong and durable, and the method of manipulating them is of the simplest character.

5 By the arrangement of the key on the pivoted latch-bar extended along the guard-cleat in the recess of the same, I provide a much more substantial, durable, and reliable device than the sliding key as it has been heretofore arranged in connection with a similar stud-hook on the riser, and a box-cleat on the seat-support, and the arrangement of the key-latch on the seat riser is a more simple and convenient contrivance than on the seat-support, as it 15 has been fixed, because in that case it has to be lifted by hand when the seat is put in position, whereas, when pivoted on the riser, it is lifted by the seat-support when put in position.

What I claim, and desire to secure by Letters Patent, is—

20 1. The hook-stud *e* and key-latch *f* *h*, attached

to the seat-riser *c*, in combination with the guard-cleat *j* on the seat-riser, and the box-cleat *b* on the seat-supporting rail *a*, said key *f* consisting of a curved prong of the latch-bar *h*, fitted on the pivot *i* of the guard-cleat, and said guard-cleat having a curved recess, *k*, for the key, substantially as described.

2. The key-latch *f* *h*, having the thumb-bit *n*, and being pivoted to the seat-riser within the guard-cleat *j*, having the recesses *k* and *l*, and notch *m*, in combination with the hook-stud *e*, attached to the seat-riser, and the box-cleat *b*, attached to the rail *a*, substantially as described.

35 In witness whereof I have hereunto signed my name in the presence of two subscribing witnesses.

ALBERT B. HALSTED.
